IDENTIFICATION CARD HOLDER

Original Filed June 11, 1930 2 Sheets-Sheet 2

UNITED STATES PATENT OFFICE

LUTHER J. KIGER, OF NASHVILLE, TENNESSEE, ASSIGNOR TO NATIONAL AUTO TAG SEAL CORPORATION, OF NASHVILLE, TENNESSEE, A CORPORATION OF TENNESSEE

IDENTIFICATION CARD HOLDER

Application filed June 11, 1930, Serial No. 460,451. Renewed November 12, 1931.

This invention relates to new and useful improvements in holders or receptacles for identification cards, operator's permits, and the like.

5 The primary object of this invention is to provide improved means for securing a holder for identification cards, operator's permit cards, and the like, to an automobile license plate.

10 A still further object of the invention is to provide a device for securing the holder to the license plate, the device for clamping the holder to the license plate being also capable of serving as a closure for one end 15 of the holder.

A still further object of the invention is to provide a holder together with a clamping device therefor, said holder and clamping device having cooperating means, whereby 20 the holder can be removed from the clamping device only by mutilation of the clamping device so that unauthorized tempering or attempts to remove the holder from the clamping device will be readily apparent.

25 Other objects and advantages of the invention will become apparent during a study of the following description, taken in connection with the accompanying drawings, wherein:

30 Figure 1 is a front elevational view of a license plate and card holder having my improved clamping device associated therewith.

Fig. 2 is a vertical sectional view taken substantially on the line 2—2 of Fig. 1.

35 Fig. 3 is a front elevational view of the improved clamping device, certain parts being broken away.

Fig. 4 is a longitudinal horizontal sectional view, taken substantially on the line 4—4 of Fig. 3.

Fig. 5 is a vertical sectional view taken substantially on the line 5—5 of Fig. 3.

Fig. 6 is a fragmentary detail view taken substantially on the line 6—6 of Fig. 1.

45 Fig. 7 is a similar view taken substantially on the line 7—7 of Fig. 1.

Fig. 8 is a rear plan view of the identification card and operator's permit holder.

50 Fig. 9 is a plan view of one end portion of the license plate to which the holder and

clamping device are adapted to be secured.

Fig. 10 is a sectional view taken substantially on the line 10—10 of Fig. 9.

Fig. 11 is a perspective view of a detail of the invention.

Referring more in detail to the drawings, it will be seen that I have designated a license plate generally by the reference character A, the same being provided adjacent its upper edge and inwardly from each end thereof with a suitable attaching slot 4.

The plate A has a tongue b struck out therefrom, the major portion of the tongue b extending parallel to the plate at the front face of the plate. At its upper end, the tongue b is provided with a vertical slot 5 for a purpose to be hereinafter made manifest.

A receptacle or holder for the operator's permit, identification card, and the like is designated by the reference character C. The holder C is preferably of elongated rectangular configuration and comprises a metallic rear wall 6, side walls 7, a bottom lower end wall 7' and a transparent front wall w through which latter wall, the identification card or operator's permit as the case may be, may be readily viewed while arranged within the holder.

The identification card or the like is passed into the casing through the top of the casing. The metallic rear wall 6 at the upper edge thereof is bent upon itself to provide a flange 8 cut away or notched intermediate its ends as at 9 to provide a pair of spaced spring-like fingers 10, each of which is suitably corrugated or otherwise formed to provide thereon teeth 11.

The holder C is adapted to be used in conjunction with a retaining device, that is formed from a single blank of metal and bent upon itself to provide an elongated casing opened at its lower end, and comprising a front wall 12 and a rear wall 13.

The front wall 12 at its opposite ends is suitably bent to provide flanges 14 receivable in internal channels 15 formed on the corresponding ends of the rear wall 13. The rear wall 13 adjacent its lower edge is bent inwardly upon itself to provide interiorly of the retaining device, a longitudinally ex-

tending spring-like retaining arm 16. The arm 16 intermediate its ends is formed inwardly as at 17. Said arm 16 at each end thereof is corrugated or otherwise formed to provide teeth 18. Teeth 11 terminate at the lower edges of the fingers 10, in effect, substantially thickening said edges; teeth 18 terminate at the upper edge of arm 16 and in effect, substantially thicken the edge of the 10 arm with the result, that when the member C has its upper portion passed upwardly into the holder R the edges of fingers 10 so modified by the provision of teeth 11 cooperate with the edge of arm 6 modified by teeth 18 15 as to positively prevent withdrawal of the holder C from the retainer R.

The intermediate portion 17 of the retaining arm 16 has a tongue 19 projecting outwardly therefrom, and adapted to extend 20 through the slot 5 in the tongue b when the entire assembly including the retaining device 25 designated generally by the reference character R and the holder C is secured to the license tag A. In this connection it will be noted that the free end of tongue b extends into the retaining device R between the rear wall 6 of the holder C and the adjacent rear wall 13 of the retainer R as suggested in Fig. 6.

Adjacent the top thereof, the retaining device R is provided with a longitudinally extending somewhat cylindrical pocket 20, within which is arranged a compressible elongated rubber tube 21 against which the upper edge 30 of the holder C bears when the holder and the contents thereof are passed into the retaining device R between the walls 12 and 13 of the retaining device.

The member 20 also acts as a closure for the upper end of the holder C to exclude dust, 40 water, and the like.

From the foregoing then, it will be seen that when the holder C has the license or identification card I as the case may be arranged therein, so as to be discernible through the 45 transparent front wall of the holder, the holder may then have its upper end passed into the retainer R sufficiently far enough, until the spring fingers 10 have passed above the upper edge of the spring retaining arm 16, so that the upper edge of the holder C will 50 abut the lower portion of the rubber 21. The rubber 21 will exert pressure on the upper end of holder C for retaining the lower edges 55 of fingers 10 modified by teeth 11 into engagement with the upper edge of the arm 16 modified by the teeth 18 in a manner before set forth.

The retainer R and holder C may then be 60 secured to the license plate A. In this connection, it will be noted that the upper end of the tongue b will be received between the rear wall 6 of the holder member C and the rear wall 13 of the retainer R, and the tongue 65 19 will be passed through the slot 5 for secur-

ing the retainer R against longitudinal movement with respect to the tongue B.

The retainer R above the cylindrical pocket 20 is provided with a double ply retaining flange 22 having a bolt receiving opening 23 adapted to align with an adjacent slot 4 in the license plate A. A retaining bolt 24 is passed through the hole 23 and slot 4 and on its free end has threadedly associated therewith a retaining cap 25.

The retaining cap 25 is provided with a metallic lining having a finger 26 sprung or stamped therefrom for engaging the shouldered head 27 of the bolt to securely clamp the retaining member R to the license plate A.

Even though I have herein shown and described the preferred embodiment of my invention, it is to be understood that the same as susceptible to changes comprehended by the spirit of the invention and the scope of the appended claims.

Having thus described my invention, what I claim as new is:

1. A license card holder comprising in combination a rear wall provided at its upper end with a pair of spaced spring-like fingers exteriorly of the holder, each of said fingers being corrugated to provide teeth, a retaining device comprising a casing-like body adapted to receive said upper end of the holder therein, a spring retaining arm formed in said body and extending for substantially the full length of the body, and having its upper edge adapted to engage the lower edges of said spring fingers when said holder is passed upwardly between the walls of said casing-like body, and said spring arm corrugated to provide teeth, the teeth of said fingers and said arm terminating at the free edges thereof.

2. A license card holder comprising in combination a rear wall provided at its upper end with a pair of spaced spring-like fingers exteriorly of the holder, each of said fingers being corrugated to provide teeth, a retaining device comprising a casing-like body adapted to receive said upper end of the holder therein, a spring retaining arm formed in said body and extending for substantially the full length of the body and having its upper edge adapted to engage the lower edges of said spring fingers when said holder is passed upwardly between the walls of said casing-like body, said spring arm corrugated to provide teeth, the teeth of said fingers and said arm terminating at the free edges thereof, and a compressible member arranged in the upper end portion of said body, and adapted to bear against the upper edge of said identification card holder to provide a closure for said holder.

3. A license card holder comprising in combination a rear wall provided at its upper end with a pair of spaced spring-like fingers exteriorly of the holder, each of said fingers being corrugated to provide teeth, a retaining

device comprising a casing-like body adapted to receive said upper end of the holder therein, a spring retaining arm formed in said body and extending for substantially the full length of the body and having its upper edge adapted to engage the lower edges of said spring fingers when said holder is passed upwardly between the walls of the casing-like body, said spring arm corrugated to provide 10 teeth, the teeth of said fingers and said arm terminating at the free edges thereof, and a compressible member arranged in the upper end portion of said body, and adapted to bear against the upper edge of said identification 15 card holder to provide a closure for said holder, and a flange projecting upwardly from the top of said body and provided with an opening adapted to register with a bolt accommodating opening in a license plate, and 20 a retaining bolt extending through said opening for securing said flange to the license plate.

4. In a device of the character described, in combination, a license plate provided with 25 a tongue struck outwardly therefrom and extending parallel to the plate, an identification card holder, a retaining device for the latter comprising a casing-like body adapted to receive said holder, said holder and said body 30 provided with cooperating means for retaining the holder in the latter against unauthorized displacement, said tongue adapted to extend upwardly into said body between one wall of said body and said holder, said tongue 35 provided with a slot adjacent the upper edge thereof, and said one wall of said body provided with a tongue projecting inwardly therefrom for reception in said slot.

5. The combination, with a license plate, 40 of a card holder and means for securing said card holder to said plate; said means comprising a metallic member including a casing-like body open at its lower end for receiving therein the upper end of the identification card 45 holder, said card holder at its upper end having its rear wall provided with spring fingers having corrugations formed therein, a spring arm formed on one wall of said casing-like body, said arm adapted to have its upper edge 50 engaging the lower edges of said fingers when said holder is disposed in said body, said arm having corrugations formed thereon, said body being provided with a cylindrical pocket having a compressible tube arranged therein 55 adapted to bear against the upper end of said holder to provide a closure for the latter, and said spring arm intermediate its ends being pressed inwardly and having a projection extending therefrom, a tongue formed on the 60 license plate adapted to pass upwardly of said body, said tongue provided with a slot adapted to receive said projection.

6. The combination, with a license plate, of 65 a card holder and means for securing said card holder to said plate; said means com-

prising a metallic member including a casing-like body open at its lower end for receiving therein the upper end of the identification card holder, said card holder at its upper end having its rear wall provided with spring fingers having corrugations formed therein, a spring arm formed on one wall of said casing-like body, said arm adapted to have its upper edge engaging the lower edges of said fingers when said holder is disposed in said body, 70 said arm having corrugations formed therein, said body being provided with a cylindrical pocket having a compressible tube arranged therein adapted to bear against the upper end of said holder to provide a closure for the latter, said spring arm intermediate its ends being pressed inwardly, and at said inwardly pressed portion provided with a projection, a tongue formed on the license plate adapted to pass upwardly of said body, said tongue 75 provided with a slot adapted to engage said projection, and a flange projecting upwardly from the top of said casing-like body, and a bolt passing through said flange and an adjacent portion of said license plate for securing 80 the flange to said license plate.

In testimony whereof I affix my signature.
LUTHER J. KIGER.
